United States Patent Office

Des. 175,298
Patented Aug. 9, 1955

175,298

CAMERA TRIPOD HEAD

Bruce H. Dalton, Los Angeles, and Edward V. Lewis,
North Hollywood, Calif., assignors to The Houston
Fearless Corporation, Los Angeles, Calif., a corpora-
tion of California

Application September 7, 1954, Serial No. 32,166

Term of patent 14 years

(Cl. D61—1)

Figure 1 is a perspective view of a camera tripod head showing our new design;

Figure 2 is a plan view of the camera tripod head;

Figure 3 is a side elevation of the camera tripod head; and

Figure 4 is a rear elevation of the camera tripod head.

We claim:

The design for a camera tripod head, substantially as shown.
